UNITED STATES PATENT OFFICE.

ROBERT E. KERBY AND FRANCES S. KERBY, OF MIAMI, FLORIDA.

DESIGN FOR A SEMINOLE INDIAN DOLL.

Application filed September 28, 1923. Serial No. 7,351. Term of patent 7 years.

To all whom it may concern:

Be it known that we, ROBERT E. KERBY and FRANCES S. KERBY, citizens of the United States, residing at Miami, in the county of Dade and State of Florida, have invented a new, an original, and ornamental Design for Seminole Indian Dolls, of which the following is the specification, reference being had to the accompanying drawing, forming part thereof.

The figure is a front view showing our new design of a Seminole Indian doll.

We claim:

The ornamental design for a Seminole Indian doll, as shown.

Signed at Miami, in the county of Dade and State of Florida, this 18th day of August, 1923.

ROBERT E. KERBY.
FRANCES S. KERBY.

In the presence of:

GEO. S. SPENCER,
J. A. KAGEY.
